CLAIM

The ornamental design for a ridge beam extrusion for a building structure, as shown and described.

DESCRIPTION

FIG. 1 is a perspective view of the ridge beam to which the design is applied and looking towards the underside thereof;

FIG. 2 is an end view of the ridge beam;

FIG. 3 is a plan view of the underside of the ridge beam;

FIG. 4 is an edge view of the ridge beam as shown in FIG. 3 turned edgewise;

FIG. 5 is a plan view looking down on the top of the ridge beam; and,

FIG. 6 shows the ridge beam turned edgewise.

It is understood that the ridge beam extrusion for a building structure shown is of indeterminate length.
